UNITED STATES PATENT OFFICE.

FERDINAND BRAUN, OF NEW YORK, N. Y.

IMPROVEMENT IN BED-LOUNGES.

Specification forming part of Letters Patent No. **177,462**, dated May 16, 1876; application filed October 2, 1875.

To all whom it may concern:

Be it known that I, FERDINAND BRAUN, of the city, county, and State of New York, have invented a new and Improved Bed-Lounge, of which the following is a specification:

Figure 1 represents a top view of my improved bed-lounge in open position. Fig. 2 is a vertical transverse section of the same on line *cc*, Fig. 1. Fig. 3 is a vertical transverse section, showing the lounge folded up.

Similar letters of reference indicate corresponding parts.

My invention relates to an improvement in bed-lounges, by which a more convenient opening and closing of the same is obtained, and a strong and steady support furnished when the lounge is thrown into position for use as a bed.

The invention consists of a lounge with folding seat section, provided with a swinging side-board, that is extended at the ends to form the supporting-legs.

The side-board is hooked by a pivoted rod to the hinged head-section, that locks, when folded back, securely to the back of the lounge.

In the drawing, *A* represents the main section; *B*, the hinged seat-section, that swings to the outside in the usual manner to form a bed. *C* is the back and *D* the lower half of the head-section, and *D'* the upper half, which is hinged to the lower to swing to the outside and form the head-piece for the hinged seat-section.

At the outer side of the seat-section *B* are strong hinges *a*, that are raised above the edge of the section, for carrying the swinging side-board *E* out with legs *E'*, extending at the ends, in one piece therewith.

The hinges allow the clear swinging around

of the side-board *E* until it assumes a vertical position in contact with the outer frame of the seat-section, when the same is thrown into open position.

The vertical position of the side-board and legs may be further secured by a suitable latch, fastening-screw, or other device, so that there may be no possibility of any detaching or sliding of the legs.

A connecting rod, *F*, is hung to an eye or staff, *b*, of the side-board, and hooked into a staple, *d*, at the outer end of the head-section *D'*, establishing thus the rigid attachment of the upper head-section in its open position with the seat-section and supporting boards.

The back *C* is provided with a groove, hook, or spring-catch, or other device for securing the upper head-section on the lower stationary section, and to the back when folded over, the lower part to form the head of the lounge.

The solid legs of the side-board and the legs of the lounge may be provided with casters, so that the whole may be moved freely, either as a lounge or bed, to any place in the room.

The lounge is readily changed to a bed, and vice versa, in an easy and convenient manner by swinging out or folding the parts in the manner shown and described.

Having thus described my invention, I claim as new and desire to secure by Letters Patent—

In a bed-lounge, the hinged seat-section, having outer side-board, with extension-legs applied to raised hinges, to swing in to vertical supporting position, substantially as specified.

FERDINAND BRAUN.
